US00D945035S

(12) **United States Design Patent** (10) **Patent No.:** **US D945,035 S**
(45) **Date of Patent:** **** Mar. 1, 2022**

(54) **FLASHLIGHT**

(71) **Applicant:** **Shenzhen Vansky Network Technology Co., Ltd.**, Guangdong (CN)

(72) **Inventor:** **Xiangang Zeng**, Guangdong (CN)

(***) **Term:** **15 Years**

(21) **Appl. No.:** **29/735,110**

(22) **Filed:** **May 18, 2020**

(51) **LOC (13) Cl.** **26-02**

(52) **U.S. Cl.** **USPC D26/46**

(58) **Field of Classification Search**

USPC D26/24, 37-51, 113
CPC F21Y 2115/10; F21Y 2113/13; F21Y 2101/00; F21Y 2103/10; F21Y 2107/40; F21Y 2105/10; F21Y 2105/18; F21Y 2113/00; F21Y 2113/10; F21Y 2113/17; F21Y 2113/20; F21L 4/005; F21L 4/027; F21L 4/085; F21L 4/08; F21L 4/045; F21L 4/00; F21L 4/02; F21L 4/022; F21L 4/04; F21L 4/025; F21L 13/00; F21L 14/02; F21L 2/00; F21V 23/0414; F21V 23/0428; F21V 23/0421; F21V 21/0965; F21V 15/01; F21V 21/0885; F21V 21/406; F21V 23/0407; F21V 23/06; F21V 33/0064; F21V 33/0084; F21V 14/025; F21V 23/04; F21V 14/065; F21V 21/084; F21V 23/003; F21V 5/006; F21V 5/04; F21V 21/08; F21V 23/0435; F21V 23/0464; F21V 31/00; F21V 31/005; F21V 33/0076; F21V 33/008; F21V 7/0075; F21V 14/045; F21V 15/012; F21V 17/12; F21V 19/02; F21V 21/0816; F21V 21/0925; F21V 21/30; F21V 23/0471; F21V 3/00; F21V 13/045; F21V 17/10; F21V 21/096; F21V 21/145; F21V 23/023; F21V 23/0442; F21V 29/70; F21V 33/0068; F21V 9/083; F21V 9/20;
